[57] CLAIM

The ornamental design for slip-on wrist case for capsule components such as compasses or thermometers, as shown and described.

DESCRIPTION

FIG. 1 is a top perspective view of a slip-on wrist case for capsule components such as compasses or thermometers showing my new design;

FIG. 2 is a bottom perspective view thereof;

FIG. 3 is a top plan view thereof;

FIG. 4 is a bottom plan view thereof;

FIG. 5 is a left side elevation view thereof of which the right side elevation view is a mirror image; and,

FIG. 6 is a front elevation view thereof of which the rear elevation view is a mirror image.
